THOMAS V. JAWORSKI, OF MANITOWOC, WISCONSIN.

BOTTLE CARRIER.

Application filed April 1, 1924. Serial No. 703,413.

This invention relates to bottle carriers and has primarily for its object to provide a simple inexpensive and efficient hand grip which can be readily attached or detached from the neck of a bottle.

A further object is to provide a carrier of the foregoing character in which it is unnecessary to disconnect any of the parts in removing the same from a bottle and vice versa.

A more specific object resides in the provision of a device of this character which is manipulated for attaching or detaching by merely rotating the handle to various positions.

With the above and other objects in view, which will appear as the description proceeds, the invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawing is illustrated one complete example of the physical embodiment of the present invention constructed according to the best mode so far devised for the practical application of the principles thereof.

Figure 1 is a front elevational view of a carrier constructed in accordance with the present invention, the same being illustrated in connection with a conventional type of bottle.

Figure 2 is a side elevation of the same.

Figure 3 is a transverse sectional view taken on the line 3—3 of Figure 1.

Referring now more particularly to the accompanying drawings, the present invention comprises a pair of yokes 1, preferably formed from resilient material, such as wire, and provided at their ends with eyes 2. As illustrated in Figure 3, the yokes 1 are preferably circular in shape to conform to the neck of the bottle B.

Connecting the yokes 1 is a U-shaped handle, also formed from resilient wire or similar material. The sides 4 of the handle are turned at their lower extremity to form eyes 5 which are adapted to receive the eyes 2 of one of the yoke members 1. Thereafter, the sides are laterally offset from the

eyes 5 and folded back to form the loops 6, 55 the upper ends 7 of which are twisted around or otherwise suitably secured to the sides 4. The lower ends of the loops 6 are slightly flared at 8 to form a socket for the reception of the eyes 2, of the other of said yokes, 60 when the handle 3 is in a vertical position and the device is mounted on the neck of the bottle.

From the foregoing description taken in connection with the accompanying drawings, 65 it is obvious that a very simple and inexpensive structure has been provided in which the parts are permanently associated together, and in which it is unnecessary to disconnect any of the parts in order to remove the device from the bottle.

In the operation of the device, it is merely necessary to rotate the handle to the right from the position illustrated in Figure 2, during which movement, the yoke carried by 75 the loop 6 will be released from its socket and allowed to slide outwardly on the loop thus allowing the device to be readily removed over the bead of the bottle. A reverse operation securely clamps the carrier 80 to the bottle.

I claim:

A bottle carrier comprising a pair of curved bottle gripping members terminating in eyelets, a U-shaped handle having 85 each of its arms provided with an integral eyelet and with an integral offset parallel portion whose outer end is wrapped about the corresponding arm, said parallel portion having an outwardly indented portion 90 adjacent said last mentioned eyelets, said last mentioned eyelets fitting within the eyelet of one of said first mentioned members and said parallel portion passing through the eyelets of the other of said first mentioned members, said parallel portions being straight between their indented portions and their wrapped ends, whereby when said handle is rocked into vertical position the parallel portions will slide freely through 95 the corresponding eyelets until such eyelets snap into the indented portions to thus lock the handle in vertical position.

In testimony that I claim the foregoing I have hereunto set my hand at Manitowoc, 105 in the county of Manitowoc and State of Wisconsin.

THOMAS V. JAWORSKI.
